(57) **CLAIM**

The ornamental design for a cap, as shown and described.

DESCRIPTION

FIG. 1 is a front view of a cap showing my new design;
 FIG. 2 is a rear view of the cap;
 FIG. 3 is a right side view of the cap;
 FIG. 4 is a left side view of the cap;
 FIG. 5 is a top view of the cap;
 FIG. 6 is a bottom view of the cap; and,
 FIG. 7 is a top rear side perspective view of the cap with the
 snap fastener shown in an open configuration.
 The short dashed broken lines along the cap depict claimed
 stitching.
